UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SHOCK-ABSORBER FOR LIGHTING DEVICES.

1,004,137.

Specification of Letters Patent. Patented Sept. 26, 1911.

Application filed November 9, 1909. Serial No. 527,065.

To all whom it may concern:

Be it known that I, REUBEN B. BENJAMIN, a citizen of the United States, residing at Chicago, in the county of Cook and State of Illinois, have invented new and useful Improvements in Shock-Absorbers for Lighting Devices, of which the following is a full, clear, concise, and exact description, reference being had to the accompanying drawing, forming a part of this specification.

This invention relates to improvements in means for guarding electric lighting devices and the like from destructive vibration shocks.

In the use of certain types of electric lamps, such as, for instance, tungsten filament lamps, it is found that some means should be provided for absorbing the shocks which would otherwise be transmitted to the lamps and destroy the delicate filaments when the lamps are installed in such places as factories and railroad stations, where excessive vibration is present. If a lighting fixture carrying metal filament lamps extends downward from the ceiling of a room located beneath heavy machinery, or under a place where heavy articles are moved about, the vibration of the ceiling will in a short time destroy the filaments of the lamps.

In the accompanying drawings—Figure 1 is a vertical sectional view of the upper portion of an electric lighting fixture provided with my improvement; Fig. 2 is a cross sectional view of the same, taken on the line 2—2 of Fig. 1 and looking downward; Fig. 3 is a cross sectional view of the same taken on the line 3—3 of Fig. 1, looking upward; and Fig. 4, a cross sectional view on line 4—4 of Fig. 1, looking downward.

In these several figures, wherein like reference numerals are used to designate the same part throughout, 5 is a U-shaped supporting member, preferably formed of a strip of heavy sheet metal. This U-shaped member has its ends 6, 6 bent outwardly at right angles with its upright side portions. These outturned ends 6, 6 are perforated for the reception of supporting screws 7, 7 when it is desired to secure the device directly to a ceiling. When it is desired to support the device upon a screw-threaded plug or the lower end of a short section of pipe a plate 8 is secured at its opposite ends 55 by suitable screws 9, 9 to the outturned end

of the U-shaped member so as to span the space between the side portions of the U-shaped member. This plate 8 has a downwardly-extending centrally-disposed collar 10 which is internally threaded for the reception of the plug or pipe above mentioned.

The U-shaped member 5 is formed with an opening in its lower portion through which passes the supporting pipe 11 which extends down to and carries the lighting device proper. This pipe 11 is arranged to vibrate slightly up and down through the opening in the U-shaped member and is supported by a spring 12 which is coiled about a sleeve 13 into which the upper end 60 of the pipe 11 screws. The sleeve 13 has secured at its upper end a rectangular plate 14 against which the upper end of the shock-absorbing spring 12 bears. The threaded sleeve 13 is secured in place in the plate 14 by flanging the end 13^a over upon the plate and is prevented from turning in the plate 14 when the pipe 11 is screwed thereto by forming the plate with notches 13^b into which the metal of the flange 13^a sinks. 65 The plate 14 being rectangular and only slightly shorter than the distance between the upright portions of the U-shaped member 5, it is evident that the plate cannot revolve, although there is sufficient space between the end of this plate and the member 5 to permit the electric lighting fixture carried by the device to swing slightly. This feature provides for the safety of the lamps in case the lower end of the lighting fixture 70 be given a side blow, as it permits the fixture to yield somewhat and thus prevent shattering of the delicate filaments of the lamps.

It is customary to conceal the upper portion of the supporting pipe for an electric lighting fixture, as well as the hickey which is usually employed, by means of a canopy having the form of an inverted bell. This canopy is usually secured directly to the iron 75 supporting pipe of the fixture or to the exterior ornamental casing tube which usually conceals the iron pipe. Were the canopy 15 of the present device secured directly to the casing tube 16 when the device is secured to a ceiling or the like the vertical movement of the fixture or the ceiling would cause the upper edge of the canopy to chatter against the ceiling unless the canopy were lowered somewhat 80

from the ceiling. This would be objectionable and I therefore provide an auxiliary exterior tube 17, which surrounds the upper end of the supporting pipe 11 and the upper end of the tube 16 where these pipes are within the canopy. This tube 17 is secured, near its lower end, to the canopy by a set screw 18 and extends a short distance below the canopy. The upper end of this tube 10 is flanged outward slightly at 19 and rests upon the U-shaped member 5. When the lighting fixture or the ceiling vibrate vertically, the pipes 11 and 16 are permitted to slide up and down relatively to the tube 17, 15 the canopy 15 and the U-shaped member 5. A pair of screws 19', 19" extend into the space above the plate 14 within the U-shaped member. These screws ordinarily have no function but are provided for the purpose 20 of preventing the spring 12 from thrusting the sleeve 13 and plate 14 upward out of the U-shaped member when the plate 8 is not employed and before the weight of the lighting fixture is present to compress the spring 25 12. The spring 12 is made of such length and strength as to balance the weight of the fixture with the top of the plate 14 slightly below the screws 19', or about as seen in Fig. 1.

30 It will be seen that with the plate 8 removed and discarded the device may be used in place of the ordinary crowfoot support, and that with the plate 8 in place the device may be screwed upon the ordinary 35 insulated support, the device then serving as a hickey.

Having thus described my invention, what I claim as new and desire to secure by Letters Patent, is:

40 1. In a shock absorber for lighting fixtures, the combination of a support having

an opening, a sleeve internally threaded for the reception of the fixture pipe, a coiled spring resting upon said support and sustaining said sleeve, means for preventing 45 rotation of said sleeve in said opening, a tubular member extending downward from said support and surrounding the fixture pipe, and a canopy secured to said tubular member.

50 2. In a shock absorber for lighting fixtures, the combination of a supporting member, an internally threaded sleeve having vertical movement in said supporting member, a spring for sustaining said sleeve, a 55 tubular member extending downward from said supporting member, and a canopy secured to said tubular member.

60 3. In a shock absorber for lighting fixtures, the combination of a supporting member, an internally threaded sleeve, a spring supported by said supporting member and sustaining said sleeve, a canopy, and means extending downward from said supporting member for sustaining said canopy.

65 4. In a shock absorber for lighting fixtures, the combination of a supporting member, a spring sustained thereby, a pipe-receiving member sustained by said spring, means for preventing rotation of said pipe-supporting member, and a canopy-supporting member secured to said first-named supporting member and arranged to permit vertical movement of said pipe-receiving member with respect to the canopy.

70 In witness whereof, I have hereunto subscribed my name in the presence of two witnesses.

REUBEN B. BENJAMIN.
